(57) **CLAIM**

I claim the ornamental design for a front or rear bumper guard, as shown and described.

DESCRIPTION

FIG. 1 is a perspective view of the front or rear bumper guard;

FIG. 2 is a top plan view thereof;

FIG. 3 is a bottom plan view thereof;

FIG. 4 is a front elevation view thereof;

FIG. 5 is a rear elevation view thereof;

FIG. 6 is a right elevation view thereof;

FIG. 7 is a left elevation view thereof; and,

FIG. 8 is a perspective view showing the front or rear bumper guard with environmental features.

Broken lines in FIG. 8 are for environmental purposes only and form no part of the claimed design.
